UNITED STATES PATENT OFFICE.

GEORGE W. BANKER, OF BROOKLYN, NEW YORK.

PACKING-CASE.

SPECIFICATION forming part of Letters Patent No. 408,684, dated August 13, 1889.

Application filed January 22, 1889. Serial No. 297,182. (No model.)

To all whom it may concern:

Be it known that I, GEORGE W. BANKER, a citizen of the United States, and a resident of Brooklyn, in the county of Kings and State 5 of New York, have invented a certain new and useful Improved Packing-Case, of which the following is a specification.

My invention relates to an improvement in packing-cases for demijohns and similar vessels or packages which require protection against fracture during transportation or use by means of cushioning devices placed between them and the inner sides of the case containing them; and, broadly stated, the invention 10 consists in a plurality of spring-buffers placed on the inside of the case, which are compressible by the insertion of the demijohn or its equivalent between them. They thus center the vessel, holding it at substantially 15 equal distance from the sides of the case all around, and also by their compressibility and elasticity they prevent fracture of the vessel consequent on jar or shock.

In the drawings the same reference-letters 25 indicate the same parts in all the figures.

In this specification and in the drawings thereof I describe and illustrate a demijohn as the vessel in conjunction with which my invention is used; but I wish it understood 30 that I do not limit myself to that special kind of vessel, nor to glass vessels, nor to those intended to contain liquids. Any vessel, box, or package which requires cushioning, as stated, may be protected by the employment of my 35 invention.

Figure 1 illustrates in elevation one of the packing-cases now used by me to contain a demijohn or like vessel. It is fitted with my invention on its interior. This figure shows 40 that the exterior of the case is as smooth and free from points or projections which would be apt to catch in adjoining articles as other cases used for the like purpose. Fig. 2 illustrates a horizontal section of the case, taken 45 on the line xx of Fig. 3. Fig. 3 illustrates a vertical section of the case, taken on the line yy of Fig. 2, or, in other words, cornerwise. Fig. 4 illustrates a longitudinal view, partly 50 in section, of one of the spring-buffers separate from the case. Fig. 5 illustrates a demijohn provided with a canvas, leather, or

equivalent covering and having handles of the same material, which method of covering the demijohns may be very advantageously employed in my improved cases, since the 55 canvas or leather covering requires but little room, thus reducing the aggregate size of the case.

A is the case. It is made, preferably, of wood. It is provided with the usual cover B, 60 which has fastening devices and handles, as shown. Any other preferred form of case may be used, and it is not essential that it should have a cover of the form shown or of any other form. 65

B' is any suitable cushioning material placed on the interior bottom of the case to protect the vessel against shock from below. C C C C are the buffers. They are composed of two practically-parallel bars D and 70 E, (see Fig. 4,) one of them—E in the present instance, although it may be the other one—being provided with dowels F, which are fastened rigidly to it by cross-pins G, and which are headed on their other end, as at H. The 75 head H moves through recesses H', somewhat larger than they are made in the bar D. The head engages with an annular shoulder I near the front edge of the bar D, and prevents the dowel from pulling out therefrom or being 80 pushed out under the action of the springs J, which encircle the dowels. The bar D is fastened securely in the corners of the case A by nailing, screwing, or in other preferred manner. The upper ends of the inner bars 85 E are beveled off, as at K, whereby the demijohn or like vessel will readily enter between the upper ends of the bars E and spread them apart upon slight pressure being applied to the top of the demijohn. Thus it is not necessary to separate the buffer-bars by hand. 90

In order that the foregoing result may be attained, the adjustment of the parts should be such that the bottom of the demijohn shall not overlap the tops of the bars E, but shall 95 fall somewhere upon the beveled surfaces K thereof. This, however, is not essential to my invention, but simply my preferred construction. The springs J rest against the opposite faces of bars D and E, as shown. 100

Referring to Fig. 5, the demijohn is covered or partially covered with a canvas protector

having handles, whereby the vessel may be conveniently manipulated. The covering is composed of a bottom piece M, upright side pieces or straps N, a circumferential band O, 5 which holds the upright pieces in place, and a neck-inclosing piece P and handles Q Q, (one or more, two being shown in the drawings,) which are also sewed to the upright straps N N and to the neck-piece P. This 10 form of covering for a demijohn has many advantages, among them that it may be made complete on a sewing-machine or otherwise, if preferred, when separate from the demijohn, and then put in place thereon, as shown, 15 and fastened securely by lacings or equivalent holding means about the neck, as seen at R. I do not claim this covering, however, in this application, it having already been patented to me in my United States Letters 20 Patent dated July 3, 1888, and numbered 385,438.

It is obvious, also, that, if preferred, the covering for the demijohn may be "solid," so called—*i. e.*, not having open spaces therein, 25 as shown—and when so made the lacing R or equivalent fastening and holding means should preferably extend down the entire side of the vessel, or practically so.

It will be obvious to those who are familiar 30 with such matters that instead of there being four buffers there may be three or any greater number, or even two only, if other means of centering the vessel be employed; also, that they need not be continuous strips 35 from the top to the bottom of the exterior case, but, on the contrary, in short sections, or only one shorter section, located where most desirable; also, that the springs may be of any preferred form other than spiral; also, 40 that it is not essential that they should encircle the dowels; also, that other means than dowels may be employed to guide and hold the bars E in place, and, generally, that there may be many alterations made in the details of 45 construction and still the essentials of my invention be employed.

The operation of the device is manifest from the foregoing description—that is to say, the demijohn or other vessel or package, either

before or after it is filled, is pressed into its 50 place between the inner-surfaces of the strips E, they being thereby somewhat compressed, thus holding the vessel, by means of elastic supports, properly centered and away from contact with the rigid sides of the case. It is 55 not essential, however, that the size of the vessel or package should be such that upon introduction between the buffers they will be compressed.

It will be noticed that by the employment 60 of a case of square or angular form in cross-section and placing the buffers in the corners thereof I secure a decided advantage, because I thereby am enabled to pack a round vessel—as, for instance, a demijohn—in the same 65 sized case that would be needful for the same vessel without the buffers, because I avail myself of the unused corner-spaces within which the buffers are placed, and in which they have ample room to operate. This feature is fully illustrated in Fig. 2, where, it will be seen, the vessel lies as close to the sides of the case as it could safely be placed if the buffers were not used, and that the buffers are located in the otherwise waste corner-spaces. 75

Having described my invention, I claim—

1. The above-described buffer for a packing-case, comprising, essentially, a fixed bar, a movable bar, guiding and holding devices 80 whereby the movable bar is held in proper position and compelled to move in proper directions, and springs interposed between the two bars, substantially as set forth.

2. In combination with a case or box of angular cross-section, a plurality of spring-buffers fastened in the interior of the box and located in the corners thereof, the buffers comprising, essentially, a fixed bar, a movable bar, guiding and holding devices for the movable bar, and springs interposed between the 90 two bars, substantially as set forth.

Signed at New York, in the county of New York and State of New York, this 19th day of January, A. D. 1889.

GEO. W. BANKER.
